ASHBEL H. HOYT, OF WAKE, MASSACHUSETTS

MUFFLER

Application filed June 3, 1930. Serial No. 458,967.

The present invention relates to mufflers primarily intended for use in silencing or deadening the exhaust explosions of internal combustion engines.

5 The primary object of the invention is to provide a muffler for internal combustion engines which will effectively reduce the violence of the exhaust gases as they are discharged into the atmosphere, thereby deadening or silencing the explosions and in a manner so as to not create a back pressure in the engine.

10 A further object of the invention is to provide a muffler of novel construction where- 15 in the gases entering an expansion chamber of novel construction are permitted to escape thru a series of expansion tubes before actually being discharged into the atmos- 20 phere.

25 Other objects and advantages of the invention will be apparent during the course of the following detailed description, taken in connection with the accompanying drawings forming a part of this specification and in which drawings:

Figure 1 is a central longitudinal section thru the improved muffler.

30 Figure 2 is a view showing the inner member in elevation and the outer tube or shell in longitudinal section.

Figures 3 and 4 are rear and front end views respectively of the improved muffler.

In the drawings, and wherein similar reference characters designate corresponding parts thruout the several views, the muffler 35 comprises an inner shell or section A and an outer section or casing B supported axially about the section A.

40 The inner section A comprises a rear- wardly tapering shell 5 preferably formed from two complementary sections divided longitudinally of the inner section and being closed at its smaller rear end by a preferably flat end wall 6. The front, larger end of the tapering shell is formed with a tubular coupling sleeve 7 arranged axially of the shell and adapted for attachment to the rear end of an internal combustion engine exhaust 45 pipe in any preferred manner whereby the 50 exhaust gases will be discharged longitudi-

nally into the shell. The shell is preferably made of metal of like thickness thruout and is formed with a series of frusto-conical portions 8 which gradually decrease in size from the open front end toward the closed end 55 wall 6. These frusto-conical portions 8 taper toward the open end of the shell with the front smaller end of the portions joined with the rear larger end of the adjacent frusto- 60 conical portion by annular tapering portions 9 having tapers greater than that of the frusto-conical portions 8 and forming a series of rearwardly directed annular shoulders 10.

The shell portions 8 and 9 provide a circumferentially grooved or corrugated shell 65 forming a series of expansion chambers 11 of decreasing volume from the front to the rear end of the shell.

Each half section of the tapering shell is provided with apertured coupling ears 12 70 which may be arranged one adjacent each end of the shell sections and one substantially midway the ends for receiving coupling bolts or other suitable fastening elements 13.

Provided in circumferential rows about the shell 5 and opening thru the tapering portions 9 is a series of preferably circular apertures 14 the combined areas of which will be greater than the area of the opening thru 80 the coupling sleeve 7. These apertures 14 are arranged in staggered relation longitudinally of the shell and each is intended to receive the smaller end of a funnel-shaped expansion tube 15. The flat end wall 6 is 85 also provided with a number of the apertures 14' for receiving a number of the funnel-shaped expansion tubes 15'. Each annular row of expansion tubes 15 as will be observed have their axes extending in forwardly con- 90 verging relation, while the annular series of tubes 15' also have their axes extending in forwardly converging relation. As will be observed, these tubes 15 and 15' are arranged to direct the exhaust gases radially and rear- 95 wardly with respect to the shell 5.

The outer section B is in the form of a plain tubular casing being open at both ends to permit free passage of air thru the casing about the shell 5.

The inner section A is supported axially within the outer section B by means of suitable brackets 20 which may be attached to the coupling ears 12 by the fastening elements 13 serving to couple the shell sections together. The outer ends of the brackets 20 may be secured in any preferred manner to the tubular casing B. The section A is mounted in the section B with the expansion tubes 15 spaced from the inner surface of the outer section whereby the gases may readily escape from the tubes and be directed in a rearward direction against the inner surface of the section A. The outer section or tubular casing is of greater length than the inner section and has its rear end projected a suitable distance beyond the rear end of the inner section whereby the gas escaping from the rear-most tubes 15 and the end tubes 15' will be directed against the outer casing.

As will be observed in Figure 2, the expansion tubes 15 are arranged in staggered relation longitudinally of the shell.

In operation, the exhaust gases entering thru the coupling sleeve 7 into the larger end of the shell will be permitted to expand in the shell and further expansion is permitted when being discharged thru the apertures 14 and 14' having a combined area greater than the intake opening at the front end of the shell. The gas escaping rearwardly thru the tubes 15 and 15' will create a suction rearwardly thru the tubular casing B and this cold air aside from cooling the gases will also act to cool the expansion tubes. The cold air being drawn into the front end of the casing will also serve to materially cool the shell 5 so that the gas in the shell will be cooled to quite some extent before escape thru the tubes. By having the total area of the apertures 14 greater than the opening thru the front end of the shell back pressure upon the engine will be prevented.

Changes in detail may be made to the form of invention herein shown and described, without departing from the spirit of the invention or the scope of the following claims.

I claim:

1. A muffler comprising a tapering shell having an inlet opening at its larger end and a wall closing its smaller end, said shell being formed with a series of connected frusto-conical portions providing a series of expansion chambers of decreasing volume from the front to the rear end of the shell, and a series of funnel-shaped expansion tubes having their smaller ends communicating with each of the expansion chambers.

2. A muffler comprising a tapering shell having an inlet opening at its larger end and a wall closing its smaller end, said shell being formed with a series of connected frusto-conical portions providing a series of expansion chambers of decreasing volume from the

front to the rear end of the shell, an annular series of rearwardly directed funnel-shaped expansion tubes communicating with each expansion chamber, and a tubular casing supported concentrically about the shell. 70

3. A muffler comprising a tapering shell having an inlet opening at its larger end and a wall closing its smaller end, said shell being formed with a series of connected frusto-conical portions providing a series of expansion chambers of decreasing volume from the front to the rear end of the shell, an annular series of radially and rearwardly directed funnel-shaped expansion tubes communicating with each expansion chamber, and a tubular casing supported concentrically about the shell. 75 80

4. A muffler comprising a tapering shell having an inlet opening at its larger end and a wall closing its smaller end, said shell being formed with a series of connected frusto-conical portions providing a series of expansion chambers of decreasing volume from the front to the rear end of the shell, an annular series of radially and rearwardly directed funnel-shaped expansion tubes communicating with each expansion chamber, and a tubular casing supported concentrically about the shell. 85 90

5. A muffler comprising an inner section embodying a series of connected frusto-conical portions of decreasing volume toward the rear end of the shell, an end wall closing the rear end of the shell, a coupling sleeve providing an opening into the front end of the shell, outlet apertures provided in the connecting sections for the frusto-conical portions and also in the rear end wall, rearwardly and radially directed funnel-shaped expansion tubes connected to the shell at each of said apertures, an outer tubular casing encircling the inner section, and means supporting the inner section axially within the outer casing. 95 100 105

6. A muffler including a shell formed with rearwardly flaring frusto-conical portions of increasing volume toward the forward end of the shell and connected by annular tapering portions providing rearwardly facing annular shoulders, a wall closing the rear end of the shell and a coupling sleeve forming an inlet opening at the front larger end of the shell, an annular series of apertures provided in each annular shoulder and in the rear end wall, a series of radially and rearwardly directed funnel-shaped expansion tubes communicating at their smaller ends with each annular series of apertures, an outer tubular casing, and brackets supporting the casing concentrically about the shell and projecting beyond the rear end thereof. 110 115 120 125

7. A muffler comprising an inner section including a longitudinally separable tapering shell provided with a series of rearwardly facing annular shoulders, an end wall clos- 130

ing the rear end of the shell, a coupling sleeve opening into the larger end of the shell and apertured coupling ears provided on each shell section, an annular series of apertures 5 provided in each annular shoulder in staggered relation longitudinally of the shell and an annular series of openings in said rear end wall, a funnel-shaped expansion tube communicating with each of said apertures, 10 said tubes being radially and rearwardly directed from the shell, an outer tubular casing enclosing the inner section, and brackets connected between the apertured coupling ears and said casing for supporting the shell axial- 15 ly within the casing.
